(57) **CLAIM**

The ornamental design for an interlocking chair, as shown and described.

DESCRIPTION

FIG. 1 is a top, front, and right side perspective view of an interlocking chair, showing my novel design;

FIG. 2 is a right side elevational view thereof, which is symmetrical with a left side elevational view thereof;

FIG. 3 is a back elevational view thereof;

FIG. 4 is a front elevational view thereof;

FIG. 5 is top plan view thereof;

FIG. 6 is a bottom plan view thereof;

FIG. 7 is a back view of the chair seat of the interlocking chair shown separately for clarity of illustration;

FIG. 8 is a top view of FIG. 7, it being understood that the bottom view is a mirror image thereof;

FIG. 9 is a front view of FIG. 7;

FIG. 10 is a right side elevational view thereof, which is symmetrical with a left side elevational view of FIG. 7;

FIG. 11 is a top view of the chair back of the interlocking chair shown separately for clarity of illustration;

FIG. 12 is a right side elevational view thereof, which is symmetrical with a left side elevational view of FIG. 11;

FIG. 13 is a front view thereof, which is symmetrical with a back view of FIG. 11; and,

FIG. 14 is a bottom view of FIG. 11.
